Samuel F. B. Morse
Inventor.

UNITED STATES PATENT OFFICE.

JAMES CUDDY, OF PITTSBURG, PENNSYLVANIA.

IMPROVEMENT IN THE MANUFACTURE OF WHITE LEAD.

GRANTED APRIL 11, 1870.

Specification forming part of Letters Patent No. 95,201, dated September 28, 1869.

To all whom it may concern:

Be it known that I, JAMES CUDDY, of Pittsburgh, Pennsylvania, have invented an Improvement in the Manufacture of White Lead; and I do hereby declare the following to be a full, clear, and exact description of the same.

My invention consists in a cheap and rapid method of converting metallic lead into white lead.

My invention further consists in an economical apparatus for showering vinegar or dilute acetic acid upon sheets of metallic lead spread upon the shelves within the casks, tubs, or other round vessels or chambers, converting the same into an acetate of lead, and preparing it for the action of carbonic acid.

In order to enable others to practice my invention, I will now proceed to describe a mode of carrying the same into effect, reference being had to the accompanying drawing, which forms a part of this specification, and in which—

Figure 1 is an elevation and cross-section of an apparatus which may be used for carrying my invention into effect. Fig. 2 is a ground plan of the same. Fig. 3 is an improved form of slat for shelves, one inch in depth, and having the lower surface one inch wide, and the upper surface one-quarter of an inch wide, by which nearly all the lower surfaces of the lead are exposed to the action of the gases within the cask or casks, or round vessels or chambers, and a more thorough decomposition of the metallic lead secured.

A A are casks, or other round vessels or chambers, of wood, stone, brick, or other suitable material, each having a door in the side for convenience in loading and unloading, and in which are placed shelves B B, or frames of wood made of strips or slats, one inch apart, upon which thin sheets of lead are laid.

They are then oxidized by a jet of steam from the pipes C C, after which they receive a shower of vinegar from the tub D (that stands upon an elevated platform, or in an upper story of the building) through the pipe E.

The upper portions of the branch pipes F F are hollow or female screws, with a narrow notch in front of each, into which a strip of

thick glass is secured, through which the operator is enabled to see the exact position of the lower pipes G G, which are male screws, each terminating in a rose or set of branching pipes, that are perforated with small holes, and marked H in the drawing.

By opening the stop cock in pipe F, and revolving the pipe G by a wrench or crank, a rotary motion is given, that showers the vinegar equally over every portion of the lead upon each shelf.

Upon the stop-cock being closed and the pipe G either raised or lowered, as the case may require, the same operation may be repeated until the lead upon all the shelves has been treated in this manner, and thus, by regulating the pressure in the pipe and the rotary motion of the cross-head through which the vinegar escapes, the casks being round and the cross-head in the center of the casks or chambers, every portion of the lead on the shelves can be thoroughly and evenly sprinkled.

Another advantage of this mode of sprinkling arises from the fact that there is no necessity for opening the door of the cask or chamber during the operation, whereby the temperature would be diminished below the point required.

The dial-plate I, which stands on the top of the cask or chamber, is numbered to correspond with the ranges of shelves in the interior, and thus insures economy and regularity in the showering of the vinegar upon the lead on the shelves, as the pipe G is raised or lowered by the operator.

I do not confine myself to this precise construction of a sprinkler, the above being but one form of its construction and operation.

A stream of carbonic-acid gas is now driven into the cask, vessel, or chamber, through the pipe K, at a temperature ranging from 85° to 100° of Fahrenheit's thermometer, as I have found that a higher temperature produces a carbonate of lead of inferior color, and also causes a serious waste of vinegar by evaporating it before an acetate has been formed.

The carbonic-acid gas is prepared by the combustion of charcoal, coke, or coal in a furnace, and is cooled to the required temperature by being passed through a worm fifty

or sixty feet long, that is kept covered by water in a suitable tank.

These operations are repeated until the manufacture of the white lead is finished, which will require about eight days.

What I claim as my invention, and desire to secure by Letters Patent, is—

1. The apparatus above described, for showering vinegar over the sheets of lead, as and for the purposes described.

2. The apparatus above described, or its equivalent, for showering vinegar over the sheets of lead, in combination with round casks or chambers, substantially as and for the purpose described.

3. The improved form of slat for the shelves, by which nearly all the under surfaces of the sheets of lead are exposed to the action of the gases within the cask or round chamber, for the purpose described.

4. The application of carbonic-acid gas at a temperature ranging from 85° to 100° (eighty-five to one hundred degrees) of Fahrenheit's thermometer, as and for the purpose described.

JAMES CUDDY.
